(57) **CLAIM**

I claim the ornamental design for a head-worn microphone, as shown and described.

DESCRIPTION

FIG. 1 is a perspective view of the head-worn microphone, FIG. 2 is a front view thereof,

FIG. 3 is a rear view thereof,

FIG. 4 is a left-side view thereof,

FIG. 5 is a right-side view thereof,

FIG. 6 is a top view thereof; and,

FIG. 7 is a bottom view thereof.

The broken lines immediately adjacent the shaded areas represent the bounds of the claimed design while all broken lines are directed to environment and are for illustrative purposes only; the broken lines shown form no part of the claimed design.
